AUTOMOBILE WHEEL COVER

William B. Pratt, Birmingham, Mich., assignor to Chrysler Corporation, Highland Park, Mich., a corporation of Delaware

Application November 2, 1959, Serial No. 58,140

Term of patent 7 years

(Cl. D14—30)

Fig. 1 is a perspective view of an automobile wheel cover showing my new design;

Fig. 2 is a sectional view taken on the line 2—2 of Fig. 3;

Fig. 3 is a front elevational view of my automobile wheel cover; and

Fig. 4 is a sectional view taken on the line 4—4 of Fig. 3.

The essential features of my design reside in the portions shown by means of full lines in the drawing.

I claim:

The ornamental design for an automobile wheel cover, substantially as shown and described.
